UNITED STATES PATENT OFFICE.

CHARLES E. MASON, OF COLUMBUS, OHIO.

DESIGN FOR A TOP PLATE FOR WATCHES.

SPECIFICATION forming part of Design No. 14,427, dated November 20, 1883.

Application filed July 17, 1883. Term of patent 14 years.

To all whom it may concern:

Be it known that I, CHAS. E. MASON, a citizen of the United States, residing at Columbus, in the county of Franklin and State of Ohio, 5 have invented a certain new and useful Design for Top Plate and Bridges for a Full-Plate Watch; and I do declare the following to be a full, clear, and exact description of the invention, such as will enable others skilled in the 10 art to which it appertains to make and use the same, reference being had to the accompanying drawing, and to letters or figures of reference marked thereon, which form a part of this specification.

15 The drawing is a representation of this invention, and is a top view.

The object of this design is to provide a new and pleasing shape for the top plate, barrel-bridge, balance-bridge, and location of the 20 train for a full-plate watch; and it consists in the novel form and configuration of parts, as hereinafter set forth.

In the accompanying drawings, the letter A designates the top plate, and B the barrel-bridge, the edge d of which is brought forward 25 in convex form centrally, completely covering the top of the barrel as well as the opening in the top plate. The ends d' d' of the edge d of the barrel-bridge are made symmetrically con-

cave, the convex curvature of the central portion being gradually merged into the concave end curves, as shown. 30

C represents the balance-bridge, the base e of which is made circular in outline to correspond with the adjacent concave end curve of the barrel-bridge B. 35

The general effect is graceful and symmetrical.

Having described this design, I claim and desire to secure— 40

The design for the barrel-bridge and balance-bridge of a full-plate watch herein described, consisting in bringing the central edge of the barrel-bridge forward in convex form, as at d, making the opposite ends of said edge, as at 45 d' d', symmetrically concave, the convex curvature of the central portion being gradually merged into the concave end curves, as shown, and providing the base of the barrel-bridge C with the circular base e, the outline of which 50 corresponds with the adjacent concave end curve of the barrel-bridge, the whole as shown and described.

In testimony whereof I affix my signature in presence of two witnesses.

Witnesses: CHAS. E. MASON.
